STAPLE PULLER FOR TEXTILE FIBERS

Ralph E. McKenna and José Alfonso Herrera, Queretaro,
Qro., Mexico

Application August 16, 1951, Serial No. 242,088

3 Claims. (Cl. 19—66)

This invention relates to drafting machinery for textile fibers and more especially to an improved staple puller, the primary object of which is to provide means for attenuating or separating textile fibers in web or sliver form.

In the course of preparation of certain textile fibers, such as wool and the like, for blending the same with other types of textile fibers, such as synthetic fibers, the wool is usually prepared in sliver or web form after which it is necessary to prepare the fibers in each sliver or web in relatively short lengths prior to blending these wool fibers with other fibers such as synthetic fibers as is well known to those familiar with the art. However, in order to prepare the relatively short lengths of groups of fibers from the fibers as previously prepared in web or sliver form, it has heretofore been necessary to cut various lengths from the previously formed web or sliver thus resulting in a substantial reduction in the length of staple of many of the fibers, particularly at the points at which the fibers have been severed. This has resulted in a considerable waste in subsequent carding and spinning processes.

An object of this invention is to overcome such defects by providing a staple puller comprising a frame provided with a first pair of rolls, preferably fluted, and one of the rolls being urged under spring pressure towards the other of the rolls, through which fibers in sliver or web form are directed and having means for intermittently imparting rotation to the first pair of rolls. A second pair of rolls is spaced a predetermined distance apart from the first pair of rolls and the rolls in this second pair of rolls may also be fluted and provided with suitable spring means for urging one of the rolls into engagement with the other. The sliver or web of the fibers passes from between the first pair of rolls, between the second pair of rolls to be discharged from the machine. The first pair of rolls are driven intermittently and the second pair of rolls are driven constantly at a substantially greater speed than the first pair of rolls to thus cause the fibers to be attenuated as they pass between the rolls and to also intermittently pull the fibers apart into relatively short lengths of sliver due to the intermittency of rotation of the first pair of rolls.

It is another object of this invention to provide a device of the type described wherein one or more slivers of fibers may be introduced to a pair of intermittently driven fluted rolls and then passed between a pair of constantly driven fluted rolls whereby the sliver will be attenuated and pulled apart into small lengths for further processing without cutting any of the fibers in said sliver.

Some of the objects of the invention having been stated, other objects will appear as the description proceeds when taken in connection with the accompanying drawings, in which—

Figure 1 is a side elevation of the improved staple puller showing the same mounted on a table and illustrating the manner in which the fibers in web or sliver form are passed through the machine;

Figure 2 is an enlarged elevation of the upper left-hand portion of Figure 1 and showing the manner in which the upper and lower fluted rolls are driven;

Figure 3 is a side elevation of the opposite side of the machine from that shown in Figure 2;

Figure 4 is a top plan view of the improved staple puller looking down on the top of Figure 3;

Figure 5 is a vertical sectional view through the improved staple puller taken along the line 5—5 in Figure 4

2

and showing the manner in which the upper and lower fluted rolls intermesh to pull the fibers therebetween;

Figure 6 is an end elevation of the machine looking at the right-hand end of Figure 3 and illustrating the sliver guide;

Figure 7 is an enlarged end elevation of the staple puller looking at the left-hand end of Figure 3.

Referring more specifically to the drawings, the numeral 10 indicates a suitable table or stand adapted to support the staple puller and it will be observed that this table or stand should be sufficiently high to accommodate a can thereunder so that a plurality of fibers in sliver form indicated at S may be taken from a can such as the can C1 and processed through the machine, in a manner to be described, and the separated portions of the sliver which have been pulled apart by the staple puller may then fall through a suitable opening 11 in the table 10 into another can such as the can C2 disposed underneath the table 10. If desired, any suitable means may be used for introducing the sliver to the machine and containing the portions thereof after processing.

A vertically disposed main frame member 15 has a lower horizontal flange portion 16 thereof suitably secured to the upper surface of the table 10 by any suitable means, such as bolts 17, and this main frame 15 may be additionally supported by a flange portion 18, if desired. Upper and lower, horizontally disposed, U-shaped frame members 20 and 21, respectively, are suitably secured at the closed ends thereof to the main frame member 15, as by bolts 22, it being observed in Figure 6 that the main frame member 15 is provided with a plurality of vertically extending slots 23 to permit vertical adjustment of the U-shaped frame members 20 and 21 relative to each other.

The U-shaped frame members 20 and 21 are of substantially identical construction and may be formed of two or more sections if desired. The U-shaped frame members extend in a horizontal plane in cantilevered relation to the main frame 15 and are spaced vertically from each other and these U-shaped frame members 20 and 21 carry the fluted rolls for attenuating and pulling apart the sliver.

The upper U-shaped frame member 20 has horizontally extending leg portions 20a and 20b, each being provided with an anti-friction bearing 23 spaced from the free end thereof in which the opposed ends of a first upper roll 24 are journaled and secured therein as by a hub portion 25. The upper roll 24 is preferably fluted or otherwise roughened to frictionally engage the sliver and spans the entire distance between the legs 20a and 20b of the upper frame member 20. The free ends of the legs 20a and 20b are each provided with an opening 26. Longitudinally extending guide projections 27 and 28 are formed in the legs 20a and 20b at the upper and lower edges of the opening 26 and a bearing block 30 having grooves, not shown, in its upper and lower edges is slidably mounted on the guide projections 27 and 28.

The bearing blocks 30 have the opposed end portions of a second upper roll 33 suitably journaled therein and confined as by a hub portion 34. The roll 33 is also preferably fluted. The bearing blocks 30 carrying the roll 33 are urged toward the roll 24 by means of compression springs 35 positioned between the bearing blocks 30 and retaining members 36 secured on the free ends of the legs 20a and 20b as by screws 37 and serving to close the openings 26. It will thus be observed that the compression springs 35 normally urge the roll 33 toward the roll 24 so that fibers passing therebetween will be frictionally engaged thereby and will be pulled between the rolls 33 and 24 as the rolls are driven in a manner to be described.

The lower U-shaped frame member 21 is substantially identical to the upper member 20 and is also provided with leg portions 21a and 21b. The leg portions 21a and 21b have suitable anti-friction bearings 40 mounted thereon spaced from the free ends thereof and in substantially vertical alignment with the bearings 23. The bearings 40 have the opposed end portions of a first lower roll 42 journaled therein and confined therein as by a hub portion 43. The first lower roll 42 spans the distance between the leg portions 21a and 21b of the frame member 21 and

is also preferably fluted. The free end portions of the leg portions 21a and 21b each have an opening 45 similar to the openings 26 in the leg portions 20a and 20b and guide projections 46 and 47 are formed at the upper and lower edges of the opening 45 and a bearing block 48 having grooves, not shown, in the upper and lower edges thereof is slidably mounted on the projections 46 and 47 in each of the openings 45 and urged toward the first lower roll 42 as by compression springs 48. The compression springs 48 are confined in the openings 45 as by a retaining member 49 suitably secured to the free ends of the legs 21a and 21b as by screws 50 and serving to close the openings 45.

Each of the bearing blocks 48 is provided with an anti-friction bearing 51 in which the opposed end portions of the second lower roll 53 are journaled and confined therein as by a hub portion 54. It will thus be observed that the compression springs 48 normally urge the second lower roll 53, which is preferably fluted, toward the first lower roll 42.

Now, fiber is introduced to the upper and lower rolls just described by means of a suitable chute 55 mounted on the uppermost edge of the main frame 15 as by brackets 56 and screws 57 and if it is desired to combine a plurality of slivers, a sliver guide 61 may be suitably secured to the main frame 15 as by the bolts 22 which secure the U-shaped frame member 29 to the main frame 15. The sliver guide 61 is preferably formed of wire bent into a plurality of guide portions 63 adapted to direct the plurality of slivers into the chute 55 so that the slivers will emerge from the right-hand end of the chute 55 in Figure 1 and they will then pass between the upper fluted rolls 24 and 33 and then downwardly between the lower fluted rolls 42 and 53.

Now, in order to drive the upper and lower rolls for attenuating the sliver and pulling apart the fibers thereof into relatively short lengths, a suitable motor 65 is mounted on the table 10 and which is provided with a shaft 66 having a pulley 67 thereon about which belts 68 are positioned which extend to the left in Figure 1 and over a main drive pulley 70 fixedly mounted on a shaft 71 which is rotatably mounted in a housing 72 secured to the main frame member 15 as at 73 and having suitable bearings, not shown, therein. The housing 72 extends transversely of the machine and the end of the shaft 71 opposed from the main drive pulley 70 has a beveled gear 74 fixedly mounted thereon which meshes with a beveled gear 75 fixedly mounted on a longitudinally extending shaft 76 rotatably mounted in a sleeve 77 which has a suitable gasket, not shown, therein and acts as a bushing for the shaft 76. The sleeve bushing 77 is suitably mounted in a bracket 78 secured to the U-shaped frame member 20 and in a bracket 79 secured to the main frame 15, as by bolts 79a.

The end of the shaft 76 opposed from the beveled gear 75 is provided with a worm 80 fixed thereon as by a pin 81 and provided with double worm teeth 82 and 83. The worm teeth 82 and 83 mesh with a worm gear 84 fixedly mounted on the end of the roll 24. It will be noted that the teeth on the worm gear 84 are spaced a relatively large distance apart from each other and the spacing of the double worm teeth 82 and 83 is such as to cause intermittent rotation of the worm gear 84 upon constant rotation of the shaft 76.

The roll 24 is also provided with a gear 85 fixed thereon adjacent one end thereof and spaced from the spur gear 84 and which gear 85 meshes with a gear 86 fixed on one end of the roll 33 for driving the roll 33 at the same speed of rotation as the roll 24, it having heretofore been described how the roll 33 is urged into engagement with the roll 24 by means of the compression springs 35 which also serve to keep the gears 85 and 86 in mesh during normal operation.

The shaft 71 is also provided with a gear 90 thereon adjacent the beveled gear 74 and which meshes with a lower roll drive gear 91 fixedly mounted on a stub shaft 93 rotatably mounted in a suitable bushing 92 suitably secured to the main frame 15. The lower roll drive gear 91 also meshes with an idler gear 94 rotatably mounted on a stud 95 suitably mounted in the leg 21a of the lower U-shaped frame member 21. The idler gear 94 meshes with a gear 96 fixedly mounted on one end of the first lower roll 42 for driving the roll 42 at a constant rate of rotation. One end of the roll 53 is also provided with a gear 97 fixed thereon which meshes with the gear 96 for

driving the same at the same rate of rotation as the roll 42, it having heretofore been described, how the roll 42 is urged into engagement with the roll 53 by means of compression springs 50 which also serve to cause the gears 96 and 97 to mesh during normal operation.

It will be observed that by the means just described, the upper rolls 24 and 33 are driven at a relatively low rate of rotation and are driven intermittently while the lower rolls are driven at a substantially higher rate of rotation and are driven constantly. It will thus be observed that the fibers in the sliver S moving between the upper fluted rolls 24 and 33 and between the lower fluted rolls 42 and 53 will be attenuated while both the upper and lower rolls are rotating due to the fact that the lower rolls are rotating at a higher speed than the upper rolls. When the upper rolls intermittently stop rotating, the sliver will be pulled apart in separate pieces of relatively short lengths due to the fact that the lower rolls will continue to rotate at a relatively high speed. These relatively short lengths of sliver will fall into a can such as can C2 and may then be removed by an operator for blending with other fibers such as synthetic fibers in any conventional or other manner.

In running fibers between fluted rolls such as in the present invention, it occasionally happens that the fibers will cling to one of the fluted rolls 42 or 53 and will be wound thereabout or lapped-up thereon which will cause the lower fluted roll 53 to move apart from the lower fluted roll 42 against the springs 48 and it is obvious that the apparatus cannot operate properly under such a condition. In order to cause the apparatus to automatically stop in such an event there are provided stop motion switches 100 and 101 secured to the retaining members 49 on the ends of the legs 21a and 21b, respectively, of the lower U-shaped frame member 21. The switches 100 and 101 are identical and are each provided with a spring pressed plunger or switch button 102 which extends through the retaining member 49 and is engaged by the sliding block 48 upon the block 48 moving to the left in Figure 3. The switches 100 and 101 are normally held in closed position and it will be observed in Figure 3, that upon the sliver lapping-up upon the lower rolls 42 or 53, the sliding block 48 will move to the left in Figure 3 moving one or both of the pins 102 inwardly to thus open the switch 100 or 101 to break the circuit to the motor 65 to automatically stop the machine, the switches 100 and 101 being disposed in series with the motor 65.

The motor 65 is provided with a wire 105 which leads to a suitable source of electrical energy, not shown, and another wire 106 which leads to one pole of a main switch 107. A wire 108 extends from the other pole of the main switch 107 to one side of the stop motion switch 100. A wire 110 leads from the other side of the stop motion switch 100 and may be suitably secured along the upper edge of the frame member 21 and extends to one side of the stop motion switch 101. A wire 111 leads from the other side of the stop motion switch 101 to the other side of the source of electrical energy, not shown.

It is thus seen that there is provided a staple puller comprising a frame having a pair of top rolls which are driven intermittently and a pair of bottom rolls which are constantly driven whereby fiber may be passed between the upper and lower rolls and may be attenuated due to the lower rolls being driven at a higher rate of speed than the upper rolls and may be pulled apart into relatively short pieces due to the intermittent rotation of the upper rolls. This prepares the fiber for blending with other fibers without the necessity of cutting the same and thus destroying the length of some of the fibers.

In the drawings and specification, there has been set forth a preferred embodiment of the invention and although specific terms are employed, they are used in a generic and descriptive sense only and not for purposes of limitation, the scope of the invention being defined in the claims.

We claim:

- An improved staple puller comprising a main frame member, an upper U-shaped frame member secured to said main frame member, a lower U-shaped frame member secured to said main frame member in spaced relation to said upper U-shaped frame member, a main drive shaft mounted on said main frame member, a pulley on said main drive shaft, a motor, means connecting the motor to said pulley driving said main shaft, said upper U-shaped frame member having a first upper fluted roll

journaled therein, a worm gear mounted on one end of the first upper fluted roll, a shaft rotatably mounted on said upper U-shaped frame member and having a worm on one end thereof adapted to mesh with said worm gear, the other end of said shaft having a beveled gear thereon, said main shaft having a beveled gear adapted to mesh with said last-named beveled gear for driving said worm, said worm having a double thread thereon to cause intermittent rotation of said worm gear and its associated first upper fluted roll, said upper U-shaped frame member having a second upper fluted roll rotatably mounted therein and driven by the first upper fluted roll, said lower U-shaped frame member having a first lower fluted roll therein, a main drive gear rotatably mounted in said main frame, said main drive shaft also having a gear thereon meshing with said main drive gear, said first lower fluted roll having a gear thereon, an idler gear mounted in said lower U-shaped frame member and meshing with said main drive gear and the gear on said first lower fluted roll for imparting constant rotation to the first lower fluted roll, a second lower fluted roll rotatably mounted in said lower U-shaped frame member and driven by said first lower fluted roll, a chute, and means for introducing fibers to said chute, said chute directing said fibers between the intermittently driven upper fluted rolls and between the constantly driven lower fluted rolls whereby said fibers will be pulled apart into the desired lengths.

2. An improved staple puller comprising a main frame member, an upper frame secured to said main frame member, a lower frame secured to said main frame member in spaced relation to said upper frame, a main drive shaft mounted on said main frame member, a pulley on said main drive shaft, a motor, means connecting the motor to said pulley driving said main shaft, said upper frame having a first upper fluted roll journaled therein, a worm gear mounted on one end of the first upper fluted roll, a shaft rotatably mounted on said upper frame and having a worm on one end thereof adapted to mesh with said worm gear, the other end of said shaft having a beveled gear adapted to mesh with said last-named beveled gear for driving said worm, said worm having a double thread thereon to cause intermittent rotation of said worm gear and its associated first upper fluted roll, said upper frame having a second upper fluted roll rotatably mounted therein and driven by the first upper fluted roll, said lower frame having a first lower fluted roll therein, a main drive

5 gear rotatably mounted in said main frame member, said main drive shaft also having a gear thereon meshing with said main drive gear, said first lower fluted roll having a gear thereon, an idler gear mounted in said lower frame and meshing with said main drive gear and the gear on said first lower fluted roll for imparting constant rotation to the first lower fluted roll, a second lower fluted roll rotatably mounted in said lower frame and driven by said first lower fluted roll, a chute, and means for introducing fibers to said chute, said chute directing said fibers between the intermittently driven upper fluted rolls and between the constantly driven lower fluted rolls whereby said fibers will be pulled apart into the desired lengths.

10 3. An improved staple puller comprising a frame, first and second upper feed rolls journaled on said frame, first and second lower staple-pulling rolls journaled on said frame and spaced beneath the respective first and second upper feed rolls, a first main drive shaft journaled on the frame, means to drive said first shaft, a worm gear mounted on one end of the first upper feed roll, a second shaft journaled on said frame and having a worm on one end thereof adapted to mesh with said worm gear, gear means for transmitting rotation from the first shaft to the second shaft for driving said worm, said worm

15 20 having a double thread thereon to cause intermittent rotation of said worm gear, its associated first upper feed roll and, thence, to the second upper feed roll, a main drive gear rotatably mounted on said frame, said main drive shaft also having a gear thereon meshing with said main drive gear, a gear on said first lower roll, an idler gear mounted in said frame and meshing with said main drive gear and said gear on the first lower roll for imparting constant rotation to the first lower roll and, thence, to the second lower roll, and means for directing fibers to and between said intermittently driven upper feed rolls, whereby the fibers move, by gravity, between the constantly driven lower rolls and are thereby pulled apart into desired lengths.
